WIRELESS RECEIVING ARRANGEMENT
WITH FRAME ANTENNA

Karl Heinrich Meier, Zurich, Switzerland, assignor to Emil Huber, Kilchberg, Zurich, Switzerland

Application April 5, 1938, Serial No. 200,219
In Switzerland April 16, 1937

2 Claims. (Cl. 250—20)

The present invention relates to a wireless broadcast receiving arrangement, in which a frame antenna is used as the effective receiving part. A receiving arrangement working with a frame antenna does not exhibit the susceptibility to disturbance of an arrangement working with an elevated antenna, however, it is necessary to locate the receiving frame, analogously to the elevated antenna, outside the local disturbance field, if its advantages are to be fully realised. Whilst it is possible without difficulty to rotate the receiving frame, by electrical or mechanical means, from the service position into the desired receiving direction, various difficulties arise in decoupling the receiving frame from neighbouring carriers of disturbing potential. Moreover the directional property of the frame is to some extent adversely affected by the fact that a part of the winding of the frame operates simultaneously as a rod antenna. This combined operation of the receiving frame therefore has the result that both electromagnetic radiation and electrostatic fields act on the receiving apparatus.

A further source of disturbance is constituted by the fact that transmitters of disturbance operating in the neighbourhood of the receiver, such as small motors, household appliances and the like, radiate disturbing electromagnetic waves, which are propagated along metallic conductors with markedly smaller losses than when they are propagated wirelessly; thus disturbing radiations arising from the neighbouring field of disturbance are propagated along the coupling cable between the antenna and the receiver and so come to affect the receiver.

According to this invention, these objections are overcome by arranging the winding forming the receiving frame, together with the coupling conductor between the receiving frame and the input circuit of the receiver and together with at least the input stage of the receiver, wholly within electrostatic screening means, the screening around the antenna being interrupted at one point but being effectively continuous electrostatically, and by arranging that these screening means have the common datum potential of the receiving apparatus as a whole, for example, earth or cathode potential. There is thus achieved a wireless receiving installation which is completely and uninterruptedly screened electrostatically.

The frame antenna can be screened electrostatically by means of a tubular sheath which is interrupted at one point, so that this screening sheath exhibits no short-circuit for the frame,

the ends of the tubular sheath being overlapped and separated by dielectric so as to maintain the electrostatic screening.

It has already been proposed to screen various parts of receiving apparatus such as a frame antenna and its coupling conductor and the input stage of the receiver itself, but so far as I am aware it has not been proposed to enclose the frame antenna, coupling conductor and the input stage of the receiver within an effectively continuous electrostatic screen.

In the accompanying drawing:

Fig. 1 shows a constructional example of the wireless broadcast receiving installation of the present invention, and

Fig. 2 shows, to a larger scale, a modification of a detail.

A rotatable antenna head 5, which is provided with a metallic coating and carries the frame antenna 6, is mounted on the mast 1 by means of ball-bearings 3, 4. The rotatable head is adjustable in its bearings about the vertical axis with the aid of a worm wheel 7, a worm 8, a worm wheel 9 and a worm 10 by means of an electric motor which is not shown. The frame antenna 6 has an outer metal tube 12 within which is disposed the frame winding 11. The winding of the frame antenna may be constructed in a simple manner by drawing the wires together into the tube 12 and connecting them together in series by means of the soldering block 13. The beginning 14 and the end 15 of the frame winding are each connected with one end of the primary coil 16 of the antenna transformer 17. The secondary winding 18 of the transformer 17 is connected with the primary coil 21 of the transformer 22 of the input circuit of the receiver by means of leads 19, 20. The frame winding 11 of the antenna 6 is coupled aperiodically with the input circuit of the receiver. The secondary coil 23 of the transformer 22 is adjustable to the transmitter to be received by means of the condenser 24. The amplification of the received waves takes place at first by the first amplifier tube 26 of the receiver which is not further illustrated. The coupling conductors 19, 20 between the antenna transformer 17 and the input circuit of the receiver are screened electrostatically by the screening means 27. This screening means 27 is connected conductively at point 28 with the casing 2 of the receiver and on the other hand by means of the bridge 29 with the metal coating of the rotatable antenna head 5. The metal tube 12 of the frame antenna is conductively connected by means of a bridge 30 with

- the rotatable head 5. In order that this metal tube 12 may not be a short circuit turn for the frame, the ends of this tube are insulated from the rotatable antenna head 5 by means of sleeves 5 31 of dielectric material, and in order that the electrostatic screening may be effectively continuous, the ends of the tube are arranged to overlap the metallic coating on the antenna head 5.
- 10 Instead of being as shown in Fig. 1, both ends of the tube 12 may be directly connected conductively with the rotatable head at their points of entry into the rotatable head. The metal tube of the antenna must then be split at some point 15 so that it forms no short circuit turn for the frame. In this case it is advantageous to split the tube at the upper midpoint of the frame. In order that the screening may be uninterrupted electrostatically, it is in addition necessary, for 20 example according to Fig. 2, which shows the upper middle part of the tube, to overlap the two halves 12', 12'' of the tube and to insulate their ends from one another by means of dielectric 32.

I claim:

1. A wireless receiving arrangement comprising a radio receiver having an initial stage and an input circuit thereinto, a frame antenna and coupling conductors between said frame antenna and said input circuit; and electrostatic screening means comprising a metallic shield enclosing said antenna, said coupling conductors, and at least said initial stage of said radio receiver, said metallic shield around the antenna being interrupted at one point, but effectively continuous 10 electrostatically, and connected to the common potential point of the receiving arrangement as a whole whereby the wireless receiving arrangement is completely screened electrostatically.

2. A wireless receiving arrangement according to claim 1 wherein said metallic shield around the antenna is of tubular form with the two adjacent ends at the point of interruption being spaced in overlapping relation with dielectric material separating said ends, whereby the electrostatic screening is substantially unaffected by the interruption.

KARL HEINRICH MEIER.
